Primary Examiner — Leanne Was-Englehart(74) *Attorney, Agent, or Firm* — The Belles Group, P.C.(57) **CLAIM**

The ornamental design for an anti-vehicle barrier, as shown and described.

DESCRIPTION

FIG. 1 is a front perspective view of an anti-vehicle barrier in accordance with the new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines depict portions of the anti-vehicle barrier that form no part of the claimed design.

1 Claim, 7 Drawing Sheets(56)
